CLAIM

The ornamental design for a mobile showroom advertising system, as shown and described.

DESCRIPTION

FIG. 1 is a front view of a mobile showroom advertising system of my design in a closed position;

FIG. 2 is a rear view thereof;

FIG. 3 is a top view thereof;

FIG. 4 is a right side thereof;

FIG. 5 is a left side view thereof;

FIG. 6 is a front view thereof in an opened position;

FIG. 7 is a rear view thereof in an opened position;

FIG. 8 is a top view thereof in an opened position;

FIG. 9 is a right side thereof in an opened position; and,

FIG. 10 is a right side perspective view thereof in an opened position.

The broken lines in the drawings depict portions of the mobile showroom advertising system that form no part of the claimed design.

1 Claim, 7 Drawing Sheets
